UNITED STATES PATENT OFFICE

FRED A. CUFF, OF MINNEAPOLIS, MINNESOTA, ASSIGNOR TO HUDSON MANUFACTURING CO., OF MINNEAPOLIS, MINNESOTA, A CORPORATION OF MINNESOTA

SPRAYER

Application filed February 28, 1927. Serial No. 171,538.

This invention relates to improvements in sprayers, of the general type used for spraying with an insecticide.

Objects of the invention are to provide an improved construction in which the liquid delivery tube is disposed wholly within the tank and pump cylinder; to provide an arrangement in which the intake end of said supply pipe is so disposed within the supply tank that it will be below the level of the tank liquid under all ordinary operating conditions; to provide a drain pocket arranged to catch the drippings from the spray orifice; and to provide such arrangements of the oil supply pipe in relation to the spray orifice as will improve atomization.

Features of the invention relate to all the details of construction, including the manner of socketing the delivery end of the cylinder within the tank, the manner of providing a pocket for catching the drippings; the manner of forming the spray orifice and the arrangement of the oil tube in relation to said orifice.

Advantages of the device are set forth in the description of the drawings forming a part of this application and in said drawings.

Figure 1 is a sectional elevation showing the tank in cross-section with the cylinder broken away at its discharge end;

Figure 2 is an end view of another form of the sprayer, incorporating a drip groove looking towards the spray orifice;

Figure 3 is a view similar to Figure 2 showing a modified construction of the pocket for catching the drippings from the orifice;

Figure 4 is a plan view further illustrating the pocket formation;

Figure 5 is a transverse section through the tank showing the relation of the pocket to the delivery end wall of the cylinder;

Figure 6 is a section illustrating a modified arrangement of the discharge orifice and oil tube;

Figure 7 is a view similar to Figure 6 showing another modification;

Figure 8 is an elevation showing the end wall of the structure of Figure 7;

Figure 9 is an end view of another modified construction of the discharge orifice in

which the delivery end of the oil tube is centered within the opening by prongs struck out from the cylinder end wall; and

Figure 10 is an end view showing a further modification somewhat similar to that illustrated in Figures 7 and 8 but showing a different arrangement of the spray openings.

The atomizing hand sprayer shown herein comprises a supply tank 1, a pump associated with the tank including a cylinder 2, having a discharge orifice 3 in that end wall adjacent the tank, said cylinder being socketed in and connected with the tank in a novel manner hereinafter to be described. The cylinder piston is indicated at 8, the piston rod at 9 and any suitable handle at 10. The pump itself may be of any preferred design.

In the forms shown in Figures 1 and 2 the end portion of the pump cylinder is socketed in the tank, and forms a sealed connection. For this purpose an opening is provided in the tank of the proper contour, and in this opening the discharge end of the cylinder is sealingly fitted, so that its discharge end wall meets the tank. In this form of the device the pocket is formed by means of an element 15 of sheet metal, bent substantially as shown and having its ends 16 secured as by soldering to the outer side of the end wall of the cylinder, while its outer edges 17 are similarly secured to the tank. The element forms a brace, and connector, which not only forms a pocket but decidedly strengthens the structure. At the junction of the outermost wall of this element with the tank is provided an indrain opening 20 leading to the interior of the tank.

By this arrangement the drippings are caught and directed towards the drain opening, and thence returned to the tank.

Figures 3, 4 and 5 illustrate a modification in which the delivery end of the cylinder is also socketed within the tank, but in this instance after forming the opening in the tank, a portion of the tank wall is pressed inwardly as at 25 to form a pocket 26, see Figure 4, in this instance having generally the configuration of a circular segment, all portions of the wall slanting toward the orificed end.

wall of the cylinder, said in-pressed pocket wall having a drain opening immediately adjacent the end wall of the cylinder as shown and the wall of the pocket slanting in a direction there-toward. This manner of forming the pocket by bending a portion of the tank wall inwardly provides a very cheap construction in which the only soldering which is necessary is that which sealingly secures the end portion of the cylinder within the tank socket, no separate pocket-forming element being necessary.

An important feature of the invention is the arrangement of the oil suction tube wholly within the tank and pump cylinder, and in such manner that the tube can be supported in its operative position only at one point, which in this instance is at its point of traversal through that portion of the cylinder wall which lies within the tank.

As shown in Figures 1, 2, and 5, the end wall of the cylinder is pressed inwardly as shown at 30 and centrally of this pressed in portion is the discharge orifice 3. Associated with the orifice and tank to obtain suction effects in the tube when air is forced through the discharge orifice, is a tube 32, which in this instance has its delivery end lying within the orifice 3, the outer diameter of the tube being less than the diameter of the orifice to form an air discharge space about the tube. The tube is bent in a direction toward the tank and traverses that portion of the cylinder wall within the tank, the tube having a straight portion which is substantially radial with respect to the axes of the cylinder and tank. The lower portion of this tube, from a point substantially adjacent the axis of the cylinder, is bent rearwardly to have its intake end disposed adjacent the inner wall of the cylinder. This intake end is disposed in this instance rearwardly of a diameter perpendicular to the cylinder axis and passing through the axes of tank and cylinder and, see Figure 1, well below a diameter passing through the tank axis parallel with the cylinder axis. Although for sake of clearness, the location of the delivery end of the tube has been described in detail, it will be understood that the arrangement is such that the intake end of the oil delivery pipe will be below the level of the tank liquid whatever the degree of axial rotation of the tank under ordinary operating conditions as when the discharge orifice is pointed upwardly.

It will be seen that the tube can be held in its position by attachment only at one point, to-wit; the point 35 where the tube passes through the wall of the cylinder. In Figure 9 additional means has been shown for centering the delivery end of the tube within the discharge orifice of the cylinder.

In the arrangement of the oil tube and air discharge orifice shown in Figure 1, the tube

is placed in the exact center of the discharge orifice. The mist produced by this type of construction and generally by the type shown in the modification is more satisfactory for some purposes than other types of atomizers where the air is blown across the open end of the tube, and in which the tube is arranged at the exterior of the orifice, this being necessary to obtain the proper spraying effects. In the present device, the amount of spraying is regulated in four ways, namely by dimensions of the cylinder, by the diameter of the air discharge orifice and by the size of the tube opening and thickness of the tube wall, as well as the relation of the discharge end of the tube to the orifice in an axial direction, so that any desired density of spraying can be produced with the proper regulation of these dimensions.

In Figure 6, the end wall of the cylinder is punched outwardly to form a conical extension 40. This arrangement has the effect of concentrating the air and spray. Figure 7 shows a modification in which the wall is pressed inwardly as in Figure 1 and then pressed outwardly to form a cone similar to that shown in Figure 6, and in this instance openings 41 are also provided arranged substantially as shown in Figures 7 and 8 to surround the central orifice 42. The effect here is to break up the spray in small particles and of directing it in less concentrated form, that is, spreading. Figure 9 shows an arrangement for centering the tube in which prongs 45 are provided, extending inwardly and radially with respect to the axis of the tube. Figure 10 illustrates a different arrangement of the openings 46, these openings corresponding to the openings 41 of Figure 7.

As shown in Figures 2, 3, 4 and 5 a vertical depression 48 provides means for guiding the surplus liquid downwardly toward the pockets 15 and 26.

Another advantage of having the tube wholly within the tank and cylinder is that it is perfectly protected for the reason that substantially no part of the tube projects so that an outside object can strike it.

I claim as my invention:

1. A device of the class described including a supply tank and a pump including a cylinder secured upon the tank, said cylinder having an end wall meeting the tank, and said wall having a discharge orifice, said tank having an inwardly pressed pocket slanting toward the meeting line of the cylinder and tank walls, said tank wall having a drain opening in that portion nearest the meeting line.

2. A device of the class described comprising a supply tank having an opening and a marginal lip for the opening pressed inwardly to form a drain pocket leading toward the interior of the tank, a pump having an end portion arranged within the opening to close

the same and having an end wall sealingly engaging the lip, said wall having a discharge orifice arranged over said drain pocket.

3. A device of the class described comprising a supply tank having an opening and a marginal lip for the openings pressed inwardly to form a drain pocket leading toward the interior of the tank, a pump having an end portion arranged within the opening to close the same and having an end wall sealingly engaging the lip, said wall having a discharge orifice arranged to deliver drippings into said drain and an oil pipe positioned with respect to the orifice within the cylinder to obtain suction effects in the tube when air is passed outwardly through the orifice.

4. A device of the class described comprising a supply tank, and a pump including a cylinder secured upon the tank, said cylinder having an end wall meeting the tank and said end wall having a discharge orifice, said tank having a pocket slanting toward the meeting line of the cylinder and tank walls, an opening leading from said pocket to the tank and arranged at that portion nearest the meeting line, the wall of said cylinder being formed to provide a channel leading toward said orifice.

5. A supply tank, a pump including a cylinder secured to the tank, and a piston for said cylinder, said cylinder having an end wall the face of which is substantially perpendicular to the long axis of the cylinder and having an orifice, and a tube leading from the tank through the cylinder wall at a point immediately adjacent and having its delivery end associated with the orifice to obtain suction effects in the tube when air is forced through the orifice, the upstanding portion of the tube which lies within the cylinder being substantially parallel with the face of the end wall and immediately adjacent the wall, to allow a maximum forward discharge stroke of the piston.

6. A device of the class described including a supply tank having a cylindrical wall and a pump including a cylinder secured upon the tank, said cylinder having an end wall having a discharge orifice, the cylindrical wall of said tank having an inwardly pressed portion forming a pocket arranged to receive drippings from the orifice.

7. A device of the class described comprising a supply tank, a pump including a cylinder secured to the tank, said cylinder having an end wall having a discharge opening the margins of which are shaped to center a supply tube, and a supply tube within the cylinder and tank having its discharge end centered in said discharge opening.

8. A device of the class described comprising a supply tank, and a pump including a cylinder secured upon the tank, said cylinder having an end wall meeting the tank and

said end wall having a discharge orifice, said tank having a pocket slanting toward the meeting line of cylinder and tank walls, and an opening leading from said pocket to the tank.

9. In a sprayer of the suction type comprising a supply tank having an opening, a pump including a cylinder capping the opening and secured to the tank, said cylinder having an end wall having a discharge orifice, a supply tube passing from the tank through that portion of the cylindrical wall of the pump which caps the tank opening, means sealingly securing the tube to the cylindrical wall, said tube being wholly within tank and cylinder, and having a discharge end centered in the discharge orifice of the end wall of the cylinder in a manner to obtain atomization of oil and mixing therewith of air forced through the cylinder out of the orifice.

10. In a sprayer of the suction type comprising a supply tank, a pump including a cylinder secured to the tank, said cylinder having an end wall having a discharge orifice, a supply tube lying wholly within the cylinder and tank, means sealingly securing the tube in operative position at the lower portion of the cylindrical wall of the pump, said means forming the sole fastening means for the tube, and the end of the tube being adapted to deliver through the orifice.

11. A device of the class described comprising a supply tank, a pump including a cylinder secured to the tank, said cylinder having an end wall punched inwardly and then outwardly to form a nozzle, said punched-in portion having openings having their axes directed outwardly toward the nozzle axis, and a supply tube within the cylinder and tank having its discharge end centered in said nozzle and spaced to provide for the projection of air through the nozzle and around said tube.

12. A device of the class described comprising a supply tank, a pump including a cylinder secured to the tank, said cylinder having an end wall having a discharge opening therein and having additional openings surrounding the discharge opening, and having their axes directed toward the axis of said discharge opening, and a supply tube within the cylinder and tank having its discharge end associated with said discharge opening to provide for the projection of air through said opening and around said tube.

In witness whereof, I have hereunto set my hand this 24th day of February, 1927.

FRED A. CUFF.
